(21) Appl. No.: **29/148,984**

CLAIM

(22) Filed: **Sep. 28, 2001**

The ornamental design for a hand wand for massaging apparatus, as shown and described.

(51) LOC (7) Cl. **24-04**
(52) U.S. Cl. **D24/200**
(58) Field of Search D24/200; 601/53, 601/54, 56-58, 46, 49, 67, 68, 70, 79, 80, 97, 101

DESCRIPTION

(56) **References Cited**

FIG. 1 is a front perspective view of a hand wand for massaging apparatus showing my new design;

U.S. PATENT DOCUMENTS

FIG. 2 is a left side elevational view thereof, of which the right side elevational view is substantially a mirror image; FIG. 3 is a top plan view thereof;

D363,552 S * 10/1995 Teo et al. D24/200
D364,686 S * 11/1995 Teo et al. D24/200
D365,639 S * 12/1995 Teo et al. D24/200
D382,645 S * 8/1997 Bergeron D24/200

FIG. 4 is a bottom plan view thereof; FIG. 5 is a front elevational view thereof; and, FIG. 6 is a rear elevational view thereof.

The broken line showing is for illustrative purposes only and forms no part of the claimed design.
